(57) CLAIM

The ornamental design for a golf putting mat as shown and described.

DESCRIPTION

FIG. 1 is a front, right and top perspective view of a golf putting mat, showing my design.

FIG. 2 is a rear, left and bottom perspective view thereof.

FIG. 3 is a front elevation view thereof.

FIG. 4 is a rear elevation view thereof.

FIG. 5 is an enlarged left side elevation view thereof.

FIG. 6 is an enlarged right side elevation view thereof.

FIG. 7 is a top plan view thereof; and,

FIG. 8 is a bottom plan view thereof.

The broken lines depict portions of the golf putting mat that form no part of the claimed design.
